UNITED STATES PATENT OFFICE.

THOMAS SCOTT COBB, OF ORMOND, FLORIDA.

DESIGN FOR A COMBINED WRENCH AND SCREW-DRIVER.

53,569.

Specification for Design.

Patented July 15, 1919.

Application filed March 29, 1919. Serial No. 286,180. Term of patent 7 years.

To all whom it may concern:

Be it known that I, THOMAS S. COBB, a citizen of the United States of America, residing at Ormond, in the county of Volusia and State of Florida, have invented a new, original, and ornamental Design for a Combined Wrench and Screw-Driver, of which the following is a specification, reference being had to the accompanying drawing, forming part thereof.

In the drawing:

Figure 1 is a front elevation of a tool showing my design;

Fig. 2 is an edge view thereof.

I claim:

The ornamental design for a combined wrench and screw driver, as shown.

THOMAS SCOTT COBB. [L.S.]
